UNITED STATES PATENT OFFICE

149,656

DESIGN FOR A BEVERAGE DISPENSER

Raymond Loewy, New York, N. Y., assignor to The Coca-Cola Company, Wilmington, Del., a corporation of Delaware

Application July 17, 1946, Serial No. 131,648

Term of patent 14 years

(Cl. D2—3)

To all whom it may concern:

Be it known that I, Raymond Loewy, a citizen of the United States and resident of New York, New York County, New York, have invented a new, original, and ornamental Design for a Beverage Dispenser, of which the following is a specification, reference being had to the accompanying drawings, forming part thereof.

Fig. 1 is a perspective view of a beverage dispenser, embodying my new design;

Fig. 2 is a side view of the dispenser illustrated in Fig. 1;

Fig. 3 is a top plan view of said dispenser;

Fig. 4 is a front view of said dispenser; and

Fig. 5 is a view taken from the rear of my dispenser.

The dominant features of my design reside in the portions shown in full lines.

I claim:

The ornamental design for a beverage dispenser, as shown and described.

RAYMOND LOEWY.
